UNITED STATES PATENT OFFICE.

JOHN F. ANDREWS, OF ST. CHARLES, ILLINOIS.

DESIGN FOR A CANOPY FOR GAS AND ELECTRIC FIXTURES.

47,769.

Specification for Design. Patented Aug. 31, 1915.

Application filed April 15, 1915. Serial No. 21,617. Term of patent 3½ years.

To all whom it may concern:

Be it known that I, JOHN F. ANDREWS a citizen of the United States, residing at St. Charles, in the county of Kane and State of Illinois, have invented a new, original, and ornamental Design for Canopies for Gas and Electric Fixtures, of which the following is a specification, reference being had to the accompanying drawing, forming part thereof.

Figure 1 is a side elevation of my new design as applied to canopies for gas and elec-

tric fixtures. Fig. 2 is a bottom plan view thereof, and Fig. 3 is a sectional view taken on the line 3—3 of Fig. 1.

I claim:

The ornamental design for the manufacture of a canopy for gas and electric fixtures as shown.

J. F. ANDREWS.
